MONKEY WRENCH

Julian W. McManus, 3733 Delmas Terrace,
Los Angeles, Calif.

Filed Dec. 6, 1962, Ser. No. 72,749

Term of patent 14 years

(Cl. D54—16)

FIG. 1.

FIG. 2.

FIG. 3.

FIG. 4.

FIG. 5.

FIGURE 1 is a side view showing my new design for a monkey wrench, the side opposite being substantially the same;

FIGURE 2 is a front view thereof;

FIGURE 3 is a bottom plan view thereof;

FIGURE 4 is a back view thereof; and,

FIGURE 5 is a top view thereof.

The dominant feature of my design resides in the portion shown in full lines. In FIGURES 3, 4, and 5, the portions shown in broken lines have been omitted for convenience of illustration.

I claim:

The ornamental design for a monkey wrench, substantially as shown and described.
